UNITED STATES PATENT OFFICE.

GEORGE C. BEIDLER, OF ROCHESTER, NEW YORK.

FILM DELIVERING AND SEVERING MEANS.

1,160,564.

Specification of Letters Patent.

Patented Nov. 16, 1915.

Application filed February 12, 1914, Serial No. 818,408. Renewed October 11, 1915. Serial No. 55,354.

To all whom it may concern:

Be it known that I, GEORGE C. BEIDLER, a citizen of the United States of America, and resident of Rochester, in the county of Monroe and State of New York, have invented 5 certain new and useful Improvements in Film Delivering and Severing Means, of which the following is a specification.

This invention relates to photography and 10 particularly to means for delivering film to a receptacle and for severing the said film to permit the severed sections thereof to be delivered to a receptacle, which receptacle may be in the nature of a dark box or it may contain solutions adapted to act on the coated 15 surface of the film.

An object of the present invention is to 20 provide novel means for cutting films into appropriate sections and for delivering the film to a receptacle by moving the said film longitudinally of the said receptacle and releasing the same as the film severing mechanism is actuated, and the invention is 25 designed for use in connection with photographing and developing apparatus and particularly in connection with the type of apparatus invented by George C. Beidler.

The invention consists in the broad idea 30 to be set forth in the claims during the prosecution of the application, the said claims to be of such scope as to give protection commensurate with the inventive act in view of the state of the art when the invention was produced.

35 In describing the invention in detail, reference will be had to the accompanying drawings forming part of this specification, wherein like characters denote corresponding parts in the several views and in which—

40 Figure 1 illustrates a vertical sectional view of a receptacle, cutters for severing the film, and rollers for feeding the film to the receptacle associated with means for reciprocating or moving one of the cutters; Fig. 45 2 illustrates a plan view of the cutters and parts associated therewith; Fig. 3 illustrates a perspective view of the reciprocating cutter and a film transferring medium associated therewith.

50 In these drawings 6 and 7 denote feeding rollers which may be suitably operated for the purpose of drawing film 8 from any source of supply, it being understood that the film is delivered to the receptacle 9 and 55 that in its travel to the receptacle 9 it passes between a stationary blade 10 and a movable

blade 11, the latter of which has its ends attached to the racks 12 and 13, which racks may be slidably supported in any appropriate framework so that they may be reciprocated through the medium of devices such as the pinion 14 one of which would be mounted at or near each end of a shaft 15, it being understood that any suitable means may be provided for rotating or partially rotating 60 the shaft 15 and that means such as the spring 16 may be attached to the rack bar and to a stationary post 17 for retracting the rack bar.

The movable blade 11 is provided with a 70 downwardly extending lip or apron 18 curved as shown in Fig. 1 so that as the blade 11 is moved toward the stationary blade 10 the member 18 will engage the film and as it is severed the film will rest on the 75 member 18 and be carried longitudinally of the receptacle 9 so long as the said blade is moving in the direction of the stationary blade. Upon a reversal of the movement of the blade 11, the film will be released from 80 the member 18 and will fall by gravity into the receptacle 9.

Any appropriate means may be substituted for the mechanism shown for reciprocating the blade, the present invention relating particularly to the means for delivering the film to the receptacle. 85

The parts heretofore described are associated with or mounted on a suitable casing 90 19 and it is to be understood that the stationary blade 10 is to be supported by the casing with relation to which the movable blade may travel.

In order to protect the stationary blade 10 from vapors or moisture arising from the developing fluids, a shield 20 is supported from and moved with the rack bars 12 and 13 and as the rack bars reciprocate the shield is moved away from or toward the stationary blade 10, according to the direction of movement of the rack bars. As a means for coupling the shield to the rack bars a cross bar 21 is provided to which the shield is attached. In Fig. 2 the relation of the stationary blade to the movable blade is illustrated in plan, it being understood that the stationary blade is to be supported by a part of the casing which is, however, not shown in said Fig. 2. 100 105

From an inspection of the drawing it will 110 be furthermore apparent that while the movable blade 11 extends diagonally transversely

of the casing, the depending portion 18 which is designed to move the film is at right angles to the length of the casing, thereby accounting for the fact that the horizontally disposed portion of the member 18 extends beyond the cutting edge of the cutting member to a greater degree at one end of the cutting member than at the other end thereof.

I claim—

- 10 1. In a machine relating to photography, a casing, a receptacle within the casing for receiving film, feeding rolls for drawing film and delivering it to the casing, a deflecting member for directing the film to the receptacle, means for cutting the film into appropriate lengths, and means engaging the cut end of the film for pushing the film longitudinally in the casing when moving in one direction and for releasing the film in the receptacle when moving in an opposite direction.
- 15 2. In a machine relating to photography, a casing, means for delivering film to the casing, a receptacle within the casing to which the film is delivered, a severing means for cutting the film, and means for engaging the film in the receptacle at its severed edge for moving the film in the receptacle.
- 20 3. In a machine relating to photography, a casing, means for delivering film to the

casing, a receptacle within the casing to which the film is delivered, a severing means for cutting the film, means for engaging the film in the receptacle at its severed edge for moving the film in the receptacle, when said means is moving in one direction and for releasing the film when moving in an opposite direction, and means for moving the film engaging member.

4. In a machine relating to photography, a casing, means for delivering film to the casing, a cutting device including means for engaging the cut edge of the film for moving the film in the casing, and means for operating the cutting means.

5. In a machine relating to photography, a casing, means for delivering film to the casing in appropriate lengths, means for moving a length of film, and means for engaging the rear end of a film for moving the same longitudinally of the casing, and means for actuating the said film engaging means.

In testimony whereof, I hereunto affix my signature in the presence of two witnesses. 55

GEORGE C. BEIDLER.
